EYE GLASS FRAME

Sara Elena Iannetta, 87 Hawkins St., Providence, R.I.

Filed Oct. 15, 1962, Ser. No. 72,113

Term of patent 3½ years

(Cl. D57—1)

FIG. 1

FIG. 2

FIG. 3

FIGURE 1 is a perspective view of an eye glass frame showing my new design.

FIGURE 2 is a front elevational view, thereof.

FIGURE 3 is a right side elevational view, thereof.

The rear not shown is substantially plain and conventional.

The left side not shown is substantially the same as the right side shown.

I claim:

The ornamental design for an eye glass frame, as shown and described.
